UNITED STATES PATENT OFFICE

THOMAS O. POE, OF MASSILLON, OHIO

MAKING AND SETTING TUBULAR WELL SCREENS

Application filed October 11, 1923. Serial No. 667,898.

The invention relates to the construction of wells by the use of tubular screens or pipes; and the objects of the improvement are to sink the pipe in a straight line into the ground, to 5 make and maintain a well hole throughout its length, of a larger diameter than the tubular screen, to completely fill and maintain the annular space between the screen and well hole with a wall of gravel or other screening 10 material, from the top to the bottom of the well, to prevent the gravel or other screening material from dropping below the lower end of the screen to utilize the weight of the gravel for sinking the screen into the well, 15 and to hold the gravel in position and prevent it from traveling faster than the screen.

The objects of the improvement are attained by securing a series of annular gravel supports or flanges around the pipe at spaced 20 intervals from the lower end toward the top of the well; which flanges may be dished in shape and the series may extend entirely to the top of the well.

An embodiment of the invention is illustrated in the accompanying drawings forming part hereof, in which—

Figure 1 is an axial section of a well constructed in accordance with the present improvement;

Fig. 2, an enlarged section of the lower portion thereof;

Fig. 3, a detached perspective view of one of the collar flanges; and

Figs. 4, 5 and 6, perspective views of modified forms thereof.

Similar numerals refer to similar parts throughout the drawings.

The pipe may be made in sections 1 or 1' of sheet iron, steel or other suitable material 40 and the sections intended to form a screen may be provided with perforations 2 in well known manner.

The collar flanges 3 may be made of sheet 45 or cast metal, with a cylindric sleeve portion 3^a which may be used as a coupling for securing adjacent pipe sections together, and a peripheral rim or flange portion 3^b which may be dish shaped as shown in Fig. 3 or may be 50 formed flat as shown at 3^{b'} in Fig. 4 or in-

verted to provide a cutting edge, as shown at 3^{b''} in Fig. 6.

The flange portions of the collar may be provided with perforations 4 to permit a free passage of water along the sides of the 55 pipe, and they may also be provided with cylindric, peripheral rims 5, as shown in Figs. 4, 5 and 6, to give a broader bearing against the well hole for keeping the pipe in line and for more effectively supporting and 60 retaining the gravel or other screening material.

In constructing a well, a hole is dug or otherwise sunk in the ground down to the water level, into which hole the pipe or screen is 65 placed and a wall of gravel or other screening material thrown in around the pipe or screen. The natural material is then removed through the tube or screen from the bottom thereof by any well known means, 70 whereupon the tube sinks or settles downward by its own weight, supplemented by the weight of the gravel held in position by the collar flanges, and supplemented also if necessary by additional weights on its upper 75 end.

As the natural material is removed from the lower end of the pipe, the collar flange there located supports the gravel wall extending up to the next collar flange and prevents the same from flowing downward into the cavity formed below the pipe; and in like manner each successive collar flange supports the gravel wall superposed thereon; and the weight of the gravel thus supported at intervals by the successive flanges serves to carry the tube downward into the cavity made by the removal of the natural material from below its lower end.

In this movement of the pipe the peripheral 80 edges of the flanges or the breadth of cylindric rims therein bear against the sides of the hole and center the pipe therein and prevent any bending or deflecting thereof from a true straight line.

I claim:—

1. A perforate, tubular well tube adapted to be inserted into an opening in the ground and provided with a series of perforate annular screening material support flanges ter- 100

minating in upwardly disposed peripheral rims arranged to bear against the wall of said opening in the ground, for supporting screening material in a cylindrical column around the tube and in direct contact with the wall of said opening in the ground, and for preventing deflection of the tube throughout the length of the tube.

2. A well tube adapted to be inserted into an opening in the ground, including a series of tubular screen sections, each screen section having an annular screening material support terminating in an upwardly disposed peripheral rim arranged to engage the wall of said opening in the ground, for supporting screening material in a cylindrical column around the tube and in contact with the wall of said opening in the ground.

3. A well tube to be inserted into an opening in the ground, including a series of tubular screen sections, each screen section having an annular screening material support flange terminating in a cylindric upturned rim arranged to engage the wall of said opening in the ground, for supporting screening material in a continuous cylindrical column from flange to flange around the tube and in direct contact with the wall of said opening in the ground, and for preventing bending in the tube from a true straight line.

In testimony that I claim the above, I have hereunto subscribed my name.

THOMAS O. POE.
